US00D989105S

(12) **United States Design Patent** (10) **Patent No.:** **US D989,105 S**
(45) **Date of Patent:** **** Jun. 13, 2023**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Frank De Jong**, San Francisco, CA (US); **Nicole R. Ryan**, San Francisco, CA (US)

(73) Assignee: **Apple Inc.**, Cupertino, CA (US)

(**) Term: **15 Years**

(21) Appl. No.: **29/843,055**

(22) Filed: **Jun. 17, 2022**

Related U.S. Application Data

(63) Continuation of application No. 29/769,853, filed on Feb. 8, 2021, now Pat. No. Des. 955,436, which is a (Continued)

(57) **CLAIM**

The ornamental design for display screen or portion thereof with graphical user interface, as shown and described.

DESCRIPTION

The FIGURE is a front view of a display screen or portion thereof with graphical user interface showing the claimed design.

The outer broken lines in the FIGURE show a display screen or portion thereof and boundary of the claimed design, and form no part of the claimed design. The other broken lines in the FIGURE show portions of the graphical user interface that form no part of the claimed design.

1 Claim, 1 Drawing Sheet

Related U.S. Application Data

continuation of application No. 29/692,759, filed on May 28, 2019, now Pat. No. Des. 910,068.
